Primary Examiner — Mary Shannon Malley*Assistant Examiner* — Dustin Andrew Griffith(74) *Attorney, Agent, or Firm* — Pharar Patents & Intellectual Property; Andrew A. Pharar(57) **CLAIM**

The ornamental design for a ring keeper, as shown and described.

DESCRIPTION

FIG. 1 is an isometric perspective view of a ring keeper;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash lines depict stitching that does form part of the claimed design.
